CLAIM

The ornamental design for a raceway cover, as shown and described.

DESCRIPTION

FIG. 1 is a top perspective view of a raceway cover showing our new design;

FIG. 2 is a bottom perspective view thereof;

FIG. 3 is an end view thereof, the opposite end view being identical;

FIG. 4 is a side view thereof, the opposite side view being identical;

FIG. 5 is a top view thereof;

FIG. 6 is a bottom view thereof;

FIG. 7 is a fragmentary detail end view of the ornamental grooved portion of the right sidewall of the raceway cover, the corresponding portion of the left sidewall being a mirror image; and,

FIG. 8 is a perspective view of the raceway cover attached to a raceway base which is shown in broken lines for illustrative purposes only and forms no part of the claimed design.
